Attorney:

UNITED STATES PATENT OFFICE.

JAMES HENRY MOSER, OF PARNASSUS, PENNSYLVANIA.

HOT-AIR FURNACE.

SPECIFICATION forming part of Letters Patent No. 770,691, dated September 20, 1904.

Application filed August 27, 1903. Serial No. 170,942. (No model.)

To all whom it may concern:

Be it known that I, JAMES HENRY MOSER, a citizen of the United States, residing at Parnassus, in the county of Westmoreland and State of Pennsylvania, have invented certain new and useful Improvements in Hot-Air Furnaces; and I do declare the following to be a full, clear, and exact description of the invention, such as will enable others skilled in the art to which it appertains to make and use the same.

My invention relates to new and useful improvements in furnaces, and more particularly to a hot-air heating-furnace made up of sections, the number of which may be increased or decreased to vary the size of the furnace.

The object of my invention is to provide a furnace of this character which will be simple in construction, durable in use, efficient in operation, and comparatively inexpensive to produce, and one which may be readily enlarged or reduced in size.

A further object is to provide means for automatically regulating the cold-air-inlet damper.

With these and other objects in view the invention consists of certain novel features of construction, combination, and arrangement of parts, as will be more fully described, and particularly pointed out in the appended claim.

Figure 1 is a perspective view of my improved hot-air furnace. Fig. 2 is a vertical longitudinal sectional view through the same. Fig. 3 is a horizontal sectional view. Fig. 4 is a vertical transverse sectional view. Fig. 5 is an inner side elevation of one of the body-sections of the furnace.

In the embodiment of my invention, as illustrated in the drawings, the numeral 1 denotes a furnace composed of two end pieces or sections 2 and 3 and two or more body-sections 4, three of the latter being shown in the drawings. Any number of said body-sections 4, which are all identical in construction and hence interchangeable, may be clamped between the front and back end pieces 2 and 3, according to the size of the furnace desired, and said body-sections are preferably in the form of integral castings, each comprising a central

rectangular body which forms the combustion-chamber of the furnace, hot-air boxes 6 upon each end of said body portion forming vertical air-heating channels or flues, and a connecting hot-air box at the top of said body portion forming a horizontal hot-air channel which connects said vertical channels and similar horizontal channels on adjacent sections. The front and rear sides of said body portion are open and adapted to align or register with the open sides of the adjacent sections or end pieces, so as to form a continuous chamber which extends through the furnace from front to rear and in which the combustion of the fuel takes place and the smoke, gases, and other products of combustion circulate. In the body 5 above the closed bottom 8 of each section 4 is supported upon ribs 9 a grate 10, which forms an ash pit or chamber 11 below the same and a fire pot or box 12 above the same, said fire-box 70 being lined by removable fire-walls 13, which are also supported by said ribs 9, and are held against the closed ends 14 of the body portion 5 of the body-sections by grooved ribs or lugs 15. In the upper portion of the body 5 above the fire-box 12 is a combustion-chamber 16, through which the smoke and other products of combustion circulate and in which is a vertical row of air-heating pipes or flues 17, disposed transversely and horizontally between 80 the ends 14 and affording communication between the vertical air-heating channels 6 to permit the pure air in said channels to circulate and become thoroughly heated. The lower ends of the channels 6 open into a cold-air space 18, formed below the furnace in the brick foundation 19, upon which it rests, and the upper ends of said channels communicate with the channels in the upper connecting hot-air boxes 7 at each end of the same. In 90 the outer wall of each of said boxes 6 on one side of the furnace is formed an opening 20, adapted to receive a moistening-kettle 21, comprising a ring or plate 22, adapted to close said opening and provided with a suitable handle 23 and a water-receptacle 24, depending from said ring 22 and disposed within the box 6, as clearly shown in Fig. 4. The cold-air space 18 beneath the furnace extends from front to rear and at its rear end is in commu- 100.

nication with the usual cold-air-inlet pipe. The front and rear sides of each of said boxes 7 are open, so as to communicate with the open sides of the adjacent boxes on either the 5 sections 4 or the end pieces 2 and 3. In the tops of said boxes 7 are formed openings having flanges or rings 25, to which hot-air-register pipes are connected. The usual dampers 26 are provided in said rings 20 to control the 10 discharge of hot-air from the furnace.

The front end piece or section 2 is a hollow casting having a central body portion formed with hot-air boxes or channels at each end and at its top similar to the sections 4. The 15 inner face or side of said front end is open at two points to register with the openings formed in the sides of the sections 4, as clearly shown in Fig. 2, and the front side or face of the same is closed except for the openings 27 20 and 28, formed in line with the fire-pot 12 and ash-pit 11 and closed by hinged doors 29 and 30, which are provided with the usual draft-dampers 31. Screw-plugs 32 close threaded openings 33, formed in the front side of the 25 said front end piece 2, for a purpose herein-after explained.

The rear end piece or section 3 is very similar to the front piece 2, the same having its inner face or side open at two places to communicate with the combustion-chamber and the upper hot-air box or channel of the last or adjacent body-section 4 and having its closed rear side or face provided with a flanged smoke-outlet opening 34, to which a smoke-pipe is attached to carry the products of combustion to a chimney or smoke-stack.

The body-sections 4 are adapted to be clamped between the end sections by passing tie bolts or rods 35 through alining apertures 40 36, formed in the several sections. The said bolts have their heads secured to the rear end piece or section 3 and extend forwardly, having their front screw-threaded ends 37 in line with the openings 33 in the front end piece 2. 45 Nuts 38 are screwed upon said threaded ends 37 to bind the several sections firmly together, a wrench being inserted through the openings 33, as indicated by the dotted lines in Fig. 2, to apply or remove said nuts from the 50 bolts.

In order to effect a smoke and air tight joint or connection between the sections, the meeting faces of each of the sections are formed with grooves 39, which extend around the 55 openings formed in the same and are adapted to receive a packing 40 in form of pliable wires, which are clamped between the grooves of two adjacent sections. It will be seen that these wires will allow for the expansion and 60 contraction of the sections and effectively prevent the escape of air, smoke, or any products of combustion.

In order to automatically regulate the amount of cold air passing into the furnace, 65 so that the air discharged from the various

registers throughout the house or building in which the furnace is located and in operation is always warm notwithstanding the condition of the fire, I control the usual pivoted damper 40, located in the cold-air-inlet pipe, 70 by a thermostatic regulating device, which comprises a thermostatic bar 41, which is disposed in the upper portion of the fire-pot 12, extending from front to rear. The front end of said expansible bar 41, which is preferably 75 of iron, is fixed in the front fire-wall and the rear end of the same extends through the rear end piece 3 and is provided with a regulating or adjusting screw 42, which is adapted to engage the shorter arm of a lever 43, pivoted 80 at 44 to a bracket on the rear end piece 3. The longer and lower arm of said lever 43 is pivotally connected by a link 45 to a crank-arm 46 on the shaft 47, which pivots the damper 40 in the cold-air-inlet pipe. The variation of the length of the bar 41, due to its expansion and contraction under the changes of temperature in the fire-box, will operate the lever 43 to open or close the damper 40, as will be readily understood. When there is 90 no fire in the fire-pot, the parts will assume the full-line position (shown in Fig. 2) and the damper 40 will be closed, thus preventing cold air passing through the furnace and into the building. When there is a fire in the furnace the parts will be moved to the dotted-line position (shown in Fig. 2) and open the damper. By means of the screw 42 the length 95 of the bar 41 may be varied to regulate the opening and closing of the damper. 100

The operation of my improved furnace will be readily understood from the foregoing description, taken in connection with the accompanying drawings. It will be seen that the heat, smoke, gases, and other products of combustion from the fire on the grates 10 will circulate through the combustion-chamber formed by the several body-sections of the furnace and about the pipes 17 in said chamber, and then discharge to the chimney or smoke-stack through the opening 34 and its attached smoke-pipe. The pure cold air which may be conveyed from any desired point through the cold-air-inlet pipe passes through the space 18 under the furnaces and 110 enters the lower ends of the vertical flues or channels formed by the boxes 4. As it passes up through said flues and circulates through the transverse flues 17, it becomes thoroughly heated by contact with the same, and then 115 passes into the horizontal flues or channels formed by the boxes 7, from which it is discharged through the openings 25 into pipes, which convey it to the registers. 120

It will be seen that my furnace is very simple in construction, and hence comparatively inexpensive to manufacture. Since the furnace is made almost entirely of castings, it is extremely strong and durable, and the large amount of heating-surface renders the same 125 130

very efficient in operation. By building the furnace in sections and uniting them as previously described the furnace may be made larger or smaller, as desired, in a simple, 5 easy, and inexpensive manner.

From the foregoing description, taken in connection with the accompanying drawings, the construction and operation of the invention will be readily understood without requiring a more extended explanation.

Various changes in the form, proportion, and the minor details of construction may be resorted to without departing from the principle or sacrificing any of the advantages of 15 this invention.

Having thus fully described my invention, what I claim, and desire to secure by Letters Patent, is—

A hot-air heating-furnace comprising a 20 plurality of intermediate body-sections, each having a chamber spaced from the sides thereof, closed at its sides, top and bottom, providing an ash-pit section, a fire-box section and a combustion-chamber section, each open 25 at its ends to communicate with a fellow section, said chamber of each intermediate body-section providing vertical air-passages at its sides, open at their lower ends for the admission of air to the heaters, a transverse air-

heating passage connecting the upper ends of 30 the vertical air-heating passages, above the combustion-chamber and having heated-air-discharging means, each of said intermediate sections being further provided with transverse air-heating passages in the combustion- 35 chamber connecting the vertical air-heating passages, front and rear end sections, having their upper ends communicating with the upper transverse air-passages of the intermediate sections and having their lower ends 40 open, said front section being further provided with passages communicating respectively with the fire-box and ash-pit formed by the several intermediate sections, means to detachably secure the intermediate and end 45 sections together, and an air-inlet chamber at the base of the furnace, communicating with the lower ends of the end sections and the lower ends of the vertical air-passages of the several intermediate sections, substantially as 50 described.

In testimony whereof I have hereunto set my hand in presence of two subscribing witnesses.

JAMES HENRY MOSER.
